SOLVENT EXTRACTION OF MINERAL OILS

Ivor W. Mills, Glenolden, Pa., assignor to Sun Oil Company, Philadelphia, Pa., a corporation of New Jersey

Application April 18, 1950, Serial No. 156,678

4 Claims. (Cl. 196—14.48)

This invention relates to solvent extraction of mineral oils, such as petroleum distillate and residual oils, and more particularly concerns a procedure for extracting two independent charge oils which have, respectively, relatively high and relatively low viscosity indexes.

In the petroleum refining art solvent extraction has been widely used for the purpose of treating oils to obtain products of higher viscosity index. Numerous solvents are known for this purpose. Such solvents are capable of preferentially dissolving aromatic constituents from the charge, so that the treatment results in an aromatic-rich extract of low viscosity index and an aromatic-lean raffinate which has a viscosity index higher than the charge. Examples of known solvents are furfural, sulfur dioxide, nitrobenzene, phenol, B-B' dichlorethyl ether, and cresylic acid-propane.

In commercial refinery practice, it frequently happens that several different charge oils derived from crudes of varying types are subjected to such solvent refining. Some stocks to be treated, for instance, may have been obtained from so-called naphthenic base crudes and therefore have relatively low viscosity indexes, while others may have been derived from mixed base or paraffinic base crudes and thus initially have relatively high viscosity indexes as compared to the naphthenic base stocks. In the usual practice these charge oils are extracted in operations which are entirely independent of each other to yield raffinate and extract products. The extract products usually contain aromatics to the extent of say 60-85%, inasmuch as the extraction conditions which are necessary for producing extract material of still higher aromatic content generally would constitute uneconomic practice for commercial refining.

I have now found that in the extraction of two independent charge oils having relatively low and relatively high viscosity indexes, respectively, an improved raffinate product can be produced in treatment of the low viscosity index stock by utilizing an integrated extraction procedure as hereinafter fully described. The improvement provided by employing such procedure can be reflected with respect either to higher viscosity index for a given yield of the raffinate product or to higher yield of the raffinate product for a given viscosity index, as compared to the results obtained in the usual practice of conducting the extractions as wholly independent operations.

According to the invention the charge stock of relatively high viscosity index is first extracted in the usual manner to yield a raffinate product and an aromatic-rich extract product. The latter is then blended with the charge stock of relatively low viscosity index and the blend is extracted to separate an aromatic-rich extract and thereby obtain the improved raffinate product.

The procedure according to the invention is illustrated schematically in the accompanying drawing in which the two charge oils are designated as "oil A" and "oil B." "Oil A" is one which initially has a relatively high viscosity index and may, for example, be a distillate or residuum stock obtained from a crude oil of the paraffin base type or mixed base type, such crudes being characterized by viscosity-gravity constants below about 0.86. "Oil B" is one of relatively low viscosity index, for example, a distillate or residuum derived from a naphthenic base type crude, which type characteristically possesses a viscosity-gravity constant above about 0.86.

The first step in the procedure comprises subjecting "oil A" to solvent extraction, as indicated schematically

2

at 10 in the accompanying drawing, to obtain "raffinate A" and aromatic-rich "extract A." Using commercially feasible extraction conditions, the latter generally will have an aromatic content of the order of 60-85%. 5 "Extract A" is then blended with "oil B" and the mixture is solvent extracted, as indicated at 11, to yield "raffinate B" and aromatic-rich "extract B." The aromatic content of "extract B" again will be of the order of 60-85%. On the other hand, "raffinate B" will have a higher viscosity index than would a raffinate produced in the same amount by extraction of "oil B" alone; or alternatively a larger amount of raffinate will be obtained if the second extraction step is conducted so as to obtain the same viscosity index as would be obtained by extraction of 15 "oil B" alone.

In each of the extraction steps of the foregoing process, any known or suitable solvent capable of preferentially dissolving aromatic hydrocarbons from the charge material can be employed, and it is to be understood that 20 the invention does not necessarily reside in the use of any particular extraction solvent. In fact, the process may also be practiced utilizing selective adsorption in place of the solvent extraction steps, for example, by treating the charge materials with an adsorbent such as 25 silica gel or activated carbon to obtain aromatic-rich and aromatic-lean products which are equivalent to the extract and raffinate products from solvent extraction.

The following example is illustrative:

A distillate oil derived from mixed base crude oil was 30 extracted with furfural, thereby yielding raffinate and extract products. Properties of the charge oil and of the products, and yields of the products, are shown in the following table:

35	Charge	Raffinate	Extract
Yield, percent of charge oil.....		76	24
A. F. I. gravity.....	27.0	31.9	13.4
S. U. visc. at 100° F.....	234	163	1834
S. U. visc. at 210° F.....	47.6	44.6	71.9
Viscosity index.....	+85	+108	-91
Aromatic content, percent by vol.....			75

The extract, which as above shown had a viscosity index 45 of minus 91 and an aromatic content of 75%, was then blended with a distillate oil derived from naphthenic base crude in a proportion of 40 parts of extract to 60 parts of the distillate oil. The mixture was extracted with furfural in amount such as to yield a raffinate approximately equivalent in volume to the amount of said distillate oil in the mixture. Properties of the distillate oil and of the resulting raffinate product were as follows:

55	Distillate Oil	Raffinate
Yield, percent (based on distillate oil).....		100 (approx.)
S. U. visc. at 100° F.....	1,569	931.
S. U. visc. at 210° F.....	73.3	64.7.
Viscosity index.....	-37	+7.
Aromatic content, percent.....	47	46

These results show that the treatment resulted in an 65 upgrading of the naphthenic distillate oil from a material having a viscosity index of minus 37 to one having a viscosity index of plus 7, without any substantial loss in volume. This was so even though the aromatic contents of the distillate oil and raffinate were about the same. It is apparent that if the second extraction step 70 were conducted so as to obtain a lower yield of raffinate, a still higher viscosity index of the raffinate product would be obtained.

While the two charge oils used in the foregoing specific example were distillate fractions, it is to be understood that the invention can be practiced with charge oils either or both of which are residuum stocks or mixtures of distillate and residuum stocks.

I claim:

1. Method which comprises solvent extracting a lubricating oil stock derived from mixed base crude oil to 80 separate an aromatic-rich extract, blending said aromatic-

rich extract, essentially free of solvent, with a lubricating oil stock as obtained by distillation from naphthenic base crude oil and having a viscosity index which is relatively low compared to that of the first-mentioned stock but higher than that of said aromatic-rich extract and then solvent extracting the blend to obtain an aromatic-rich extract and a raffinate product, whereby said raffinate product has a higher viscosity index than is obtainable, for the same amount of raffinate product, from the last-named lubricating oil stock alone.

2. In a method for solvent extracting a relatively low viscosity index lubricating oil stock derived from crude oil of relatively high viscosity-gravity constant to separate an aromatic-rich extract from a raffinate product, the improvement which comprises mixing said lubricating oil stock, as obtained by distillation from crude oil of relatively high viscosity-gravity constant, with a substantially solvent-free aromatic-rich extract obtained from a relatively high viscosity index lubricating oil stock derived from crude oil of relatively low viscosity-gravity constant, said aromatic-rich extract having a lower viscosity index than the said lubricating oil stock with which it is mixed and then extracting the mixture, whereby the resulting raffinate product has a higher viscosity index than is obtainable, for the same amount of raffinate product, from said low viscosity index stock alone.

3. Method which comprises solvent extracting a relatively high viscosity index lubricating oil stock derived from crude oil of relatively low viscosity-gravity constant to separate an aromatic-rich extract, blending said aromatic-rich extract, substantially free of solvent, with a

5 relatively low viscosity index lubricating oil stock as obtained by distillation from crude oil of relatively high viscosity-gravity constant and having a viscosity index which is relatively low compared to that of the first-mentioned stock but higher than that of said aromatic-rich extract, and then solvent extracting the blend to obtain an aromatic-rich extract and a raffinate product, whereby said raffinate product has a higher viscosity index than is obtainable, for the same amount of raffinate product, from the last-named lubricating oil stock alone.

10 4. Method according to claim 3 wherein the first-named lubricating oil stock is derived from crude oil having a viscosity-gravity constant below 0.86 and the last-named lubricating oil stock is derived from crude oil having a viscosity-gravity constant above 0.86.
